UNITED STATES PATENT OFFICE.

WILLIAM G. GOODWIN AND ABRAHAM L. FREEDLANDER, OF DAYTON, OHIO, AS
SIGNORS, BY MESNE ASSIGNMENTS, TO THE DAYTON RUBBER MANUFACTURING
COMPANY, OF DAYTON, OHIO, A CORPORATION OF OHIO.

BELT-CUTTING MACHINE.

Application filed March 3, 1924. Serial No. 696,467.

This invention relates to belt-cutting machines and is designed as an improvement upon that part of the machine set forth in the application of Messrs. Russell, Farrell, and Meyer, filed Jan. 17, 1924, Ser. No. 686,740, which relates to means for preventing the endless roll of belting from slipping or shifting sideways on the supporting rolls during the period of cutting the roll into individual belts, of which pending application The Rubber Development Company, the assignee of this application, is the owner, as shown by the assignment of record in the Patent Office.

15 The feature of preventing the roll of belting material from shifting on the supporting rolls longitudinally of their axes is carried out in the present invention by the provision of means to adjust the relation of the two 20 rolls out of parallelism, so that one roll will be positioned at a slight inclination to the other; whereby the roll of belting is prevented from shifting laterally in either direction and in this way the roll of belting is made 25 to revolve in a certain definite plane so that the knives used to sever the roll into individual belts will properly act on the roll of belting and cut it along straight lines.

It is a further object of the invention to 30 provide a rotating gauge which will indicate to the operator in which direction the roll of belting is tending to move and thereby enable him to adjust the roller up or down as conditions may require.

35 In the example illustrated, only the upper roll is made adjustable to vary its parallelism to the other roll but it is obvious that either or both rolls may be adjusted in carrying this object into effect.

40 In the accompanying drawings:

Figure 1 is a front elevation of a belt cutting machine embodying our invention;

Figure 2 is a sectional view taken on the line 2—2 of Figure 1;

45 Figure 3 is a sectional view taken on the line 3—3 of Figure 1;

Figure 4 is a sectional view taken on the line 4—4 of Figure 1 and

Figure 5 is a detail of the locking collar.

50 In these drawings, the numeral 1 designates the general base of the machine to which our invention is applied. The base 1 has a top 2 on which is fitted a bed-like part 3, the upper portion of which, as shown at 4,

is fashioned into stationary ways on which 55 is mounted the cutting knives for severing the roll of belting into individual belts. A table 5 is formed with a trough to receive the dripping of the water which is delivered to the endless roll of belting material during 60 the cutting operation.

At each side of the machine, as shown in Figure 1, are standards 6 and 7, the former at its base constituting a compartment 8 in which is located for driving mechanism for 65 operating the arbor or shaft of the lower supporting roller. These standards 6 and 7 have formed on them ways 9 and 10 respectively.

On the ways 9 are mounted slides 11 and 70 on the ways 10 are mounted slides 12. These slides are adapted to be adjusted up and down more or less, as fully set forth in the above mentioned application.

We shall now refer to the manner of 75 mounting the upper supporting roller 13 in relation to the slides 11 and 12. The slide 11 forms a bearing 14 carried by a sleeve 15, having a slot 16. A shaft 17 is eccentrically mounted in the bearing 14 and is 80 adapted to have one end of the roller 13 mounted thereon. The sleeve 15 and its supporting bar 18 are mounted on the slide 11 in any suitable manner.

For the other end of the shaft 17 there is 85 provided a bearing 19 mounted in a sleeve 20 which is sustained by member 21 secured to the supporting bar 18 extended rigidly from the slide 11. The sleeve 20 has apertures 21^a which receive pivot screws 22 90 which enter the bearing 19 and permit a slight rocking movement to the same and the shaft 17 carried thereby. This pivotal mounting permits the other end of the shaft to be adjusted for the purpose desired, as 95 hereinafter set forth. Spacing collars 23 are interposed between two members of the supporting bar 18 and held in position by bolts and nuts 24. In order to steady the bearing sleeve 20 and prevent vibration, a 100 bracket 25 is mounted on the slide 12 and extended under the sleeve 20 to support it as indicated at 26. This bracket is mounted to swing away from the bearing sleeve 20 by means of its pivotal connection with rod 105 27 which extends through the bracket. The primary purpose of swinging the bracket 25 away from the bearing sleeve 20 is to permit

the endless roll of belting material, to be presently referred to, to be slipped over the supporting roll 13.

Referring now to the manner of mounting the lower supporting roller 28, one end of this roller receives a screw threaded projection on a stud shaft 29 carried by the standard 6. This shaft may be driven in any suitable manner, as by a motor fully shown and described in the above mentioned application. A hand lever 31 is provided for starting or stopping the mechanism for for rotating the shaft 29.

The lower supporting roller 28 is the roller which is positively rotated, the roller 13 merely travelling with the endless roll of belting which is positively driven by the roller 28.

Thus by the adjustment of the upper roller 13 with respect to the position of the lower roller the belting material is put under proper tension, while the rotation of the lower roller causes the belting to travel against the knives by which it is to be severed into separate belts.

Referring to the other end of the lower supporting roller 28 and the manner of mounting same, it will be seen that a stud shaft 32 carries a block 33 adapted to rest within the jaws 34 of a bracket 35 connected with the slide 12 by being pivoted on the rod 27 carried by the slide. This bracket has lugs 36 and 37 which fit upon the rod 27 and give vertical rigidity to the bracket.

These parts are sufficiently tight as to cause the bracket 35 to maintain its normal position in sustaining its end of the roller 28, but which is yet capable of being swung laterally to permit the endless roll of belting 40 to be slipped over the supporting roller 28 at the same time it is slipped over the corresponding end of the other supporting roller 13.

The instrumentalities for severing the roll 45 of belting material into individual endless belts and the manner of mounting and operating such instrumentalities are the same as in the application above referred to and it will therefore not be necessary to illustrate 50 or describe them in detail. 38 designates one of the movable plates mounted on the ways 4. This plate carries one of the knife holding bars 39 having oblique slots 40 therein for the reception of the knife blades 41. Hand wheels 42 and 43 are provided for adjusting the knives to and from the roll of belting. Two wheels have been used to enable the operator to employ both hands or to have a hand operated shaft near him 55 no matter whether he is standing at the front of the machine nearest the right hand side, or nearest the left hand side. To prevent the knives being accidentally adjusted against the lower roller 28, a stop device 60 consisting of a rod 44 and a thumb nut 45 is

provided. During the cutting operation water is supplied to the roll of belting through the pipe 46. A hood 47 held by an arm 48 aids in properly directing the water.

We shall now refer to the means for preventing the endless roll of belting material from travelling lengthwise on the rollers 13 and 28. Such rolls of belting material when formed are usually smaller in the central part than at either end and one end is often 75 of greater diameter than the other end. The means for placing the roll of belting material under tension after placed on the rollers 13 and 28 will tend to make the roll of belting material uniform throughout before the 80 cutting knives are brought into contact therewith, but it has been found in practice that the greater circumference of one end of the roll of belting will not always be entirely equalized by the tensioning members, 85 and that when the roll of belting is rotated at a very high rate of speed as is essential for the cutting operation, the roll of belting will tend to travel lengthwise on the rollers 13 and 28. To overcome this disadvantage 90 we have provided a special form of adjusting and locking device which have been found in practice to be efficient and prevent the roll of belting from travelling longitudinally on the rollers. In the present instance we have applied our invention to the upper roller 13, but it will be understood that it may be readily applied to either roll or to both, and we therefore do not wish to be limited to the particular application of 95 the invention here shown and described.

In Figure 1 we have shown a rotating gauge 49 so positioned that when the roll of belting material has been placed on the rollers 13 and 28 and the rollers adjusted by the 100 means provided on the slides 11 and 12 for putting the roll of belting under tension, the edge of the roll adjacent the rotating gauge should just touch the same when the roll of belting is being rotated. If after tensioning the roll of belting and starting the machine, it is found that the roll of belting tends to travel away from the rotating gauge or toward it, which latter will be indicated by a buckling of the roll of belting, the operator will know that the roll of belting is of greater diameter at one end or the other. To overcome this tendency of the roll of belting to travel lengthwise of the rollers by reason of one end being larger than the 110 other, we have provided means for adjusting one end of one of the rollers carrying the same and maintaining it in such adjusted position, so that the rollers 13 and 28 will not be parallel to one another. This means 115 consists of an adjusting handle 50 having a reduced portion 51 which enters a recess in the bearing 14. This handle may be moved through the slot 16 in the sleeve 15 to raise 120 or lower the shaft 17 and hence the roller 125 130

carried thereby. After this adjustment is accomplished, we have provided means for maintaining such adjustment. To this end a shaft 53 having an operating handle 54, 5 is mounted in the slide 11. This shaft 53 has a reduced portion 54a screw-threaded at its end which is adapted to enter a screw-threaded block 55 securely mounted in said slide 11. A locking collar 56 abuts against 10 the shoulder 57 on the shaft 17 and has a cut-away portion adapted to have a locking fit with the bearing 14. When the adjusting handle 50 has been moved to the desired extent, the handle 54 attached to the shaft 15 53 is operated until the locking collar 56 is forced into engagement with the bearing 14 thereby locking it against movement. It will thus be seen that the end of the roller 13 at the left hand side of the machine may be ad- 20 justed up or down which will provide for preventing the roll of belting from moving either to the right or to the left of the machine. If the roll of belting is tending to move to the left of the machine, the roller 25 13 will be raised and if it is tending to move to the right of the machine, the roller will be lowered, the rotating gauge 49 serving to inform the operator of any lengthwise travel of the roll of belting. This rotating gauge 30 also serves as a stop for the roll of belting.

Having thus fully described our invention, what we claim as new and desire to secure by Letters Patent, is:—

1. In a machine of the character described, 35 the combination with superposed supporting rollers adapted to carry and rotate an endless roll of belting, of adjusting devices applied

to one end of one of said rollers and adapted to raise and lower said end to vary the vertical distance between the axes of the rollers, 40 and means for pivotally mounting the other end of said roller to which the adjusting means is applied.

2. In a machine of the character described, the combination with supporting rollers 45 adapted to carry and rotate an endless roll of belting, means to effect such rotation, means for adjusting one of said rollers relatively to the other to exert tension on the roll of belting, means to determine the position of said roll of belting relatively to said rollers, of means for adjusting one end 50 of one of said rollers to vary the vertical distance between the axes of the rollers, and means for pivotally mounting the other end 55 of said roller.

3. In a machine of the character described, the combination with supporting rollers adapted to carry and rotate an endless roll of belting, means for tensioning 60 said roll of belting, means for rotating said roll of belting, means to determine the lateral travel of said roll of belting relatively to said rollers, means to adjust one end of one of said rollers and means to pivotally 65 mount the other end of said roller, cutting instrumentalities adapted to be adjusted relatively to said roll of belting and to sever the same into a plurality of belts.

In testimony whereof, we affix our signatures.

WILLIAM G. GOODWIN.
ABRAHAM L. FREEDLANDER.
